UNITED STATES PATENT OFFICE.

WARNER LOWDER VESTAL, OF SAN BERNARDINO, CALIFORNIA.

RURAL-DELIVERY MAIL-BOX.

SPECIFICATION forming part of Letters Patent No. 694,219, dated February 25, 1902.

Application filed August 30, 1901. Serial No. 73,855. (No model.)

To all whom it may concern:

Be it known that I, WARNER LOWDER VESTAL, a citizen of the United States, residing at San Bernardino, in the county of San Bernardino and State of California, have invented new and useful Improvements in Rural-Delivery Mail-Boxes, of which the following is a specification.

This invention relates to new and useful improvements in rural-delivery mail-boxes; and the primary object thereof is to provide a cheap, simple, and durable box provided with a series of individual compartments, the doors of which may be controlled by a single set of levers, so that they may be simultaneously opened by the collector.

A further object is to provide means whereby the doors may be separately and independently opened.

20 A further object is to provide an automatic time-indicating device for denoting the different periods of collection.

A still further object is to provide a safety attachment against any part of the box being incidentally left insecure.

Other objects, as well as the peculiar construction of the invention, will be specifically described hereinafter and illustrated in the accompanying drawings, in which—

30 Figure 1 is a perspective view of the mail-box constructed in accordance with my invention. Fig. 2 is a front view of the same, parts being broken away and the doors being removed. Fig. 3 is a vertical longitudinal section of the portion of the casing illustrating the mail-receptacle. Fig. 4 is a sectional view on the line 4 4, Fig. 2. Fig. 5 is a similar view on the line 5 5, Fig. 2. Fig. 6 is a still further section on line 6 6, Fig. 2. Fig.

40 Fig. 7 is a detail section of one of the independent door-locks. Fig. 8 is a like view of the spring-actuated hinge. Fig. 9 is a detail view of the bolt to lock the door. Fig. 10 is a detail view illustrating one of the strips of the indicating-belt. Fig. 11 is a detail view of the actuating-lever for said belt. Fig. 12 is the lever-actuating means. Fig. 13 is a fragmentary view of the lock-actuating bar. Fig. 14 illustrates a modified form of the same, and

50 Fig. 15 is a sectional view of the same. Referring now to the drawings by numerals of reference, 1 designates a casing provided

with a plurality of separate and independent compartments 2. These compartments are spaced apart by suitable partitions, and each compartment is normally closed by a door 3. In order to automatically open said door, I provide a spring 4, the ends of which abut against the hinge-plates. An intermediate portion of the said spring is coiled around the pindle of the hinge, so that as soon as the lock is released the doors will be immediately swung open. Each door is closed by a lock 5, a separate and distinct key being used for each compartment. However, from each lock-bolt projects a laterally-extending pin 5^a, which is adapted to be engaged simultaneously by one of the longitudinally-moving operating-rods 6 or 7, which carry downwardly-projecting lugs or trips 8 to abut against the pin and withdraw the bolt from its strike at determined intervals.

In one end of the casing is a partitioned compartment 9, in which is arranged two pivoted elbow-levers 10 and 11, one above the other. One arm of each of these levers is provided with a weight 10^a, while at one of the other arms are connected link-rods 12, whereby the sliding rods 6 and 7 are operatively secured to said elbow-levers. A vertical connecting bar or rod 13 is also carried by the arms 14 of said levers 10 and 11, and intermediate the ends of said rod 13 is an offset or flange which may be grasped by the collector, and by pulling down on said lever 13 the rods 6 and 7 will be operated, so as to withdraw the bolts. As soon as the connecting-rod 13 is released the weights will throw the rods 6 and 7 back to their normal position, thus permitting the compartments to be closed. Each of these compartments is supposed to be used by individuals and are in the nature of delivery-boxes. Each individual will possess a key which will only fit the lock designed for his particular compartment. As the collector or delivery-carrier reaches the box he will open the doors 15 through the medium of a key fitting in the lock 15^b thereof, which doors are designed to protect the interior of the compartment 9. By pressing on the rod 13 all of the doors will be opened, as above described, and any mail may be readily distributed into the various compartments 2.

15 designates a door which closes the com-

partment 9, and this door carries two laterally-projecting pins 15^a, which rest under the arms 14, so that any accidental displacement of the arms resulting in the doors being prematurely opened will be obviated. As one of the doors is opened the arms 16, secured to a suitable base-plate 17 and fastened to the inside of said door, will be caused to operate the pivoted actuating-arm 18, and thus rotate the endless belt 19 to successively cause the time-cards 20 to appear adjacent the slot 21 in the opposite door to indicate the time the next collection will be made. This arm 18 will intermittently engage the respective slides on which the time-cards are carried through the medium of a cleat 23, of which one is secured to each strip. Owing to the peculiar location of the arms 16 and plates 17, this belt will be actuated each time the door 15 is opened and closed.

In the rear of the mechanism just described is the receiving-receptacle 25 of the box, having a receiving-chute 26 at the top thereof. The pivoted door 27 of this receptacle is located in the end of the box and is normally closed by a sliding bolt 28, which is secured to the door 25 by a link connection 29. As the door 15 is swung open the bolt 28 will be withdrawn from its stroke, and thus permit the door 27 to drop down, whereby the contents of the box 25 may be removed. In order to guard against the collector leaving the receiving-chute 25 open to inspection by unauthorized persons, I have provided a bell-crank lever 30, which is pivoted to the bottom of the receptacle 25, and at one end thereof is a link-bar 31, which is in engagement with said door. To the other end of the lever 30 I secure a reciprocating plunger-lever 32, which projects through the receptacle containing the operating mechanism and bears against the edge of the door 15 when it is open. Should the collector fail to close the door of the receptacle 25, he would be reminded of his error owing to the fact that the door 15 could not be closed until the door 27 was closed, thus withdrawing the plunger-lever 32.

The number of cards carried by the indicator will be in accordance with the number of collections made and allowed by the Post-Office Department, and I therefore reserve the right to change the number to suit the requirements and convenience of the community in which the box is located. In the event that the indicator does not designate the correct time for the next delivery the proper card may be brought adjacent the slot 21 by opening and closing the door 15 a sufficient number of times. I have illustrated but eight individual compartments in the drawings; but it is obvious that any number might be made to suit the requirements of the special community without departing from the spirit of the invention. If desired, a suitable provision may be made on this box for attaching

a Weather Bureau report, a clock, barometer, or thermometer without detracting from the appearance or affecting the operation of the device. As these elements, however, are all well known, I have thought best not to describe or illustrate them. I also reserve the right to make such slight changes and alterations as would suggest themselves from time to time without affecting the scope or departing from the spirit of my invention.

Having thus fully described my invention, what I claim, and desire to secure by Letters Patent, is—

1. In a device of the character described, the combination with a casing provided with a plurality of independent compartments normally closed by spring-actuated doors, a locking device carried by each door, a separate compartment arranged adjacent the first-named ones, rods slidably mounted in the compartments' partitions, means mounted in the separate compartment for operating the said rods simultaneously, an indicator arranged in the separate compartment and a swinging door for said compartment carrying means for actuating the indicator.

2. In a device of the character described, the combination with a casing provided with a plurality of independent compartments, doors carried by the casing, one for each compartment, a separate compartment arranged in one end of the casing, longitudinally-moving rods provided with trips to release the said doors, levers pivotally mounted in the said separate compartment and having one of their ends connected to the said rods, a bar connecting the opposite ends of the levers, and arms projecting outwardly from the said levers and having weighted ends for returning the said rods to their normal positions.

3. In a device of the character described, the combination with a casing provided with a plurality of independent compartments, swinging doors normally closing said compartments, a second compartment arranged in said casing, means carried by the casing and controlled from the last-named compartment, whereby the swinging doors may be simultaneously released, a mail-receptacle in the rear of the second-named compartment, a door secured thereto, a bell-crank lever pivoted within the said receptacle, a link-bar having one of its ends in engagement with said door and the other end pivotally connected to one end of the said lever, a plunger-lever connected to the other end of the said bell-crank lever, said plunger-lever adapted to bear against the edge of the door of the said separate compartment when it is open.

4. In a device of the character described, the combination with a casing provided with a plurality of independent compartments each normally closed by a spring-actuated swinging door, means for independently releasing each door, longitudinally-moving rods provided with trips adapted to operate said locks

- for simultaneously releasing said doors, a separate compartment from which the said rods may be operated, a door closing the same, and an indicator controlled by said door for determining the time of collection.
5. In a device of the character described, the combination with a casing provided with a plurality of independent compartments, swinging doors normally closing said compartments, a second compartment arranged in said casing, means carried by the casing and controlled from the last-named compartment whereby the swinging doors may be simultaneously released, a mail-receptacle in the rear of the second-named compartment, a door secured thereto and levers arranged in said casing so that the door in the second compartment cannot be closed until the door in the mail-receptacle is closed.
10. In a device of the character described, the combination with a casing provided with a plurality of independent compartments normally closed by self-opening doors, a locking device carried by each door, a separate compartment arranged adjacent to the first-named ones, rods slidably mounted in said independent compartments' partitions, and means mounted in the separate compartment for operating the said rods simultaneously.
15. In a device of the character described, the combination with a casing provided with a plurality of independent compartments, each normally closed by a swinging door, of a second compartment arranged in said casing, means within the last-named compartment for releasing the swinging doors, and a mail-receptacle in the rear of the second-named compartment and normally closed by a door.
20. In a device of the character described, the combination with a casing provided with a plurality of independent compartments, each normally closed by a door, a separate compartment arranged adjacent the first-named compartments, a swinging door for the said compartment, an indicator arranged in the last-named compartment, and comprising an endless belt, cleats on the endless belt, a lever pivotally mounted adjacent to the said belt and adapted to engage the said cleats, and a pair of arms arranged one above the other and rigidly secured to the door of the last-named compartment and adapted to actuate the said lever.
25. In a device of the character described, the combination with a casing provided with a plurality of independent compartments, each normally closed by a door, a separate compartment arranged adjacent the first-named compartments, a swinging door for the said compartment, an indicator arranged in the last-named compartment, and means carried by the casing and controlled from the last-named compartment whereby the swinging doors may be simultaneously released, a mail-receptacle in the rear of the second-named compartment, a door secured thereto and levers arranged in said casing so that the door in the second compartment cannot be closed until the door in the mail-receptacle is closed.
30. In a device of the character described, the combination with a casing provided with a plurality of independent compartments, each normally closed by a door, a separate compartment arranged adjacent the first-named compartments, a swinging door for the said compartment, an indicator arranged in the last-named compartment, and means carried by the casing and controlled from the last-named compartment whereby the swinging doors may be simultaneously released, a mail-receptacle in the rear of the second-named compartment, a door secured thereto and levers arranged in said casing so that the door in the second compartment cannot be closed until the door in the mail-receptacle is closed.
35. In a device of the character described, the combination with a casing provided with a plurality of independent compartments, each normally closed by a door, a separate compartment arranged adjacent the first-named compartments, a swinging door for the said compartment, an indicator arranged in the last-named compartment, and means carried by the casing and controlled from the last-named compartment whereby the swinging doors may be simultaneously released, a mail-receptacle in the rear of the second-named compartment, a door secured thereto and levers arranged in said casing so that the door in the second compartment cannot be closed until the door in the mail-receptacle is closed.
40. In a device of the character described, the combination with a casing provided with a plurality of independent compartments, swinging doors normally closing said compartments, a second compartment arranged in said casing, means carried by the casing and controlled from the last-named compartment whereby the swinging doors may be simultaneously released, a mail-receptacle in the rear of the second-named compartment, a door secured thereto and levers arranged in said casing so that the door in the second compartment cannot be closed until the door in the mail-receptacle is closed.
45. In a device of the character described, the combination of a casing divided into a plurality of independent compartments, of spring-actuated doors carried by said casing, one for each compartment, a locking device carried by each door for normally holding it closed, and each adapted to be unlocked from the exterior separately, a second compartment arranged in said casing, and means located in said second compartment for unlocking all of the doors simultaneously.
50. In a device of the character described, the combination of a casing provided with a plurality of independent compartments, each normally closed by a door, a separate compartment arranged adjacent the first-named compartments, a swinging door for the said compartment, an indicator arranged in the last-named compartment, and comprising an endless belt, cleats on the endless belt, a lever pivotally mounted adjacent to the said belt and adapted to engage the said cleats, and a pair of arms arranged one above the other and rigidly secured to the door of the last-named compartment and adapted to actuate the said lever.
55. In a device of the character described, the combination of a casing provided with a plurality of independent compartments, each normally closed by a door, a separate compartment arranged adjacent the first-named compartments, a swinging door for the said compartment, an indicator arranged in the last-named compartment, and means carried by the casing and controlled from the last-named compartment whereby the swinging doors may be simultaneously released, a mail-receptacle in the rear of the second-named compartment, a door secured thereto and levers arranged in said casing so that the door in the second compartment cannot be closed until the door in the mail-receptacle is closed.
60. In a device of the character described, the combination of a casing provided with a plurality of independent compartments, each normally closed by a door, a separate compartment arranged adjacent the first-named compartments, a swinging door for the said compartment, an indicator arranged in the last-named compartment, and means carried by the casing and controlled from the last-named compartment whereby the swinging doors may be simultaneously released, a mail-receptacle in the rear of the second-named compartment, a door secured thereto and levers arranged in said casing so that the door in the second compartment cannot be closed until the door in the mail-receptacle is closed.
65. In a device of the character described, the combination of a casing provided with a plurality of independent compartments, each normally closed by a door, a separate compartment arranged adjacent the first-named compartments, a swinging door for the said compartment, an indicator arranged in the last-named compartment, and comprising an endless belt, cleats on the endless belt, a lever pivotally mounted adjacent to the said belt and adapted to engage the said cleats, and a pair of arms arranged one above the other and rigidly secured to the door of the last-named compartment and adapted to actuate the said lever.
70. In a device of the character described, the combination of a casing provided with a plurality of independent compartments, each normally closed by a door, a separate compartment arranged adjacent the first-named compartments, a swinging door for the said compartment, an indicator arranged in the last-named compartment, and means carried by the casing and controlled from the last-named compartment whereby the swinging doors may be simultaneously released, a mail-receptacle in the rear of the second-named compartment, a door secured thereto and levers arranged in said casing so that the door in the second compartment cannot be closed until the door in the mail-receptacle is closed.
75. In a device of the character described, the combination of a casing provided with a plurality of independent compartments, each normally closed by a door, a separate compartment arranged adjacent the first-named compartments, a swinging door for the said compartment, an indicator arranged in the last-named compartment, and means carried by the casing and controlled from the last-named compartment whereby the swinging doors may be simultaneously released, a mail-receptacle in the rear of the second-named compartment, a door secured thereto and levers arranged in said casing so that the door in the second compartment cannot be closed until the door in the mail-receptacle is closed.

In testimony whereof I affix my signature in presence of two witnesses.

WARNER LOWDER VESTAL.
